UNITED STATES PATENT OFFICE.

EMIL BEDARD, OF PAWTUCKET, RHODE ISLAND, ASSIGNOR TO HEMPHILL MANUFACTURING COMPANY, A CORPORATION OF RHODE ISLAND.

KNITTING-MACHINE FOR MAKING ANTIRAVEL COURSES IN HOSIERY.

1,250,773.

Specification of Letters Patent. Patented Dec. 18, 1917.

Application filed August 31, 1915. Serial No. 48,233.

To all whom it may concern:

Be it known that I, EMIL BEDARD, citizen of the United States, residing at Pawtucket, Rhode Island, have invented certain new 5 and useful Improvements in Knitting-Machines for Making Antiravel Courses in Hosiery, of which the following is a specification.

For making an anti-raveling course of 10 stitches in the leg of a stocking it has been proposed heretofore to so control the needles that certain needles will knit while others tuck in said course, the said machine being provided with jacks under alternate needles, 15 and having automatically operating controlling cams for the needles whereby the needles are divided so that alternate needles will perform their knitting operation in the ordinary way by being advanced above the 20 line of the fabric to take new yarn and to get the old stitch below the latch so that this stitch will be cast when the needle is drawn down at the stitch point, whereas the other needles will not be advanced high 25 enough to cause their latches to free themselves from the old stitch, but will hold said old stitch and take on new yarn and form a second stitch, both of which will be cast off simultaneously, thus forming stitches in this 30 course on every other needle, after which all of the needles proceed with regular knitting.

My present improvement is designed to 35 simplify the machine by dispensing with the jacks and by dispensing with certain needle and jack controlling cams heretofore proposed, and substituting therefor a simpler cam arrangement.

For this purpose I employ needles having 40 latches of normal length alternating with needles having long latches throughout the needle circle. I also employ the usual knitting cam set of the well known Banner machine, and in addition I employ a needle 45 elevating cam which is automatically adjustable for causing the needles to perform either their regular knitting or to form tuck stitches on the alternate needles having the long latches.

50 The invention is shown in the accompanying drawing which is of diagrammatic form showing the cam set and the knitting wave.

In these drawings the ordinary set of cams 55 for operating the needles as used on the

well known Banner machine is indicated generally at A, including the stitch cams 4, 4', a guard cam 5, a lower central cam 5*, instep cam 6, instep lowering cam 6', narrowing picks 2 and widening picks 3. The 60 needle circle is made up of heel and toe and instep needles, the heel and toe needles, as in ordinary practice, occupying one-half of the needle circle, while the instep needles occupy the other half of the needle circle, 65 and as in ordinary practice also the instep needles may have longer butts than the heel and toe needles to be operated upon by the instep cam 6, though it will be understood that I do not limit myself to the use of 70 needles having different lengths of butts or to the use of the particular instep cam 6 shown herein.

Every other needle *a* throughout the needle circle including both the heel and toe 75 and instep needles has a latch of ordinary length, while the needles *b* alternating in position throughout the needle circle with the needles *a* have long latches. Interposed between the instep cams 6, 6' and the ordinary set of needle cams A I arrange a vertically moving cam 7 on the outer side of the ordinary cam ring 8, and I provide above this cam a fixed guard cam 9. In the particular embodiment of my invention herein 80 described, when the cam 7 is elevated to the position shown at 7* all the needles throughout the needle circle will be elevated so that the latches of all the long latch needles as also the latches of all the short 90 latch needles will be moved up through the old stitches, and said old stitches will be cleared from the latches, both long and short, onto the stems of the needles and when the needles are advanced by the cam 4 95 regular knitting will be performed. The needle butts are indicated at 10, and the direction of movement for round knitting is in the direction of the arrow, it being understood that the machine is preferably one 100 of the rotary cylinder type.

As just stated, when the elevating cam 7 is in its elevated position all of the needles throughout the needle circuit will perform ordinary knitting. When the cam is shifted downwardly so that its point is below or even with the upper edge of the cam ring 8, which upper edge is the normal plane of the needle butts, these needle butts will pass the cam 7 and below the cam 9 without being 105 110

elevated at this point. They will, however, be advanced as in the ordinary Banner machine when they reach the upper surface of the cam 4. The long latch needles, however, 5 will not be advanced high enough by cam 4 to carry their latches up through the old loops, and hence these long latch needles will retain their loops and will take yarn from the feed finger indicated at B, and upon the 10 retraction of the needles by the stitch cam 4' the short latch needles will cast their loops, but the long latch needles will hold their loops, and on the next round the cam 7, having been first elevated, the long latch 15 needles will clear both loops onto their stems and these will be cast by the stitch cam and tuck stitches will therefore be formed on these needles. When the cam 7 is elevated for ordinary knitting, the long latch needles, 20 as well as the short latch needles, will be elevated above the knitting plane indicated by the dotted line α — α , and the fabric loops will get below the latches of all of the needles and notwithstanding the fact that all 25 of the needles are immediately retracted to their normal plane by the guard cam 9, ordinary knitting will be proceeded with because the needles will ride up over the cam 4, and they will all receive thread from the 30 feeder B and upon their retraction by the cam 4' the old loops will be cast off and ordinary knitting will be performed. The cam 7 may be operated in various ways, but as an example I show a rod 11 connected 35 with this cam, said cam being connected to a lever 12 pressed by a spring 13 and having its forward end resting upon a cam 14 of the well known cam drum of the Banner machine. This cam is provided with a low part 40 at 15, and when this comes around under the end of the lever 12, said lever will fall and lower the cam 7 and the parts will remain in this position for one round to allow the long 45 latch needles to take on the new thread while the old loops are still held on the latches of these needles.

The cam drum then makes a movement lifting the cam 7 so that all of the needles will cast off.

50 What I claim as my invention is:

1. In a circular knitting machine, needles having short latches alternating with needles having long latches throughout the needle circle, a yarn feeder, stitch cam means, 55 a movable needle elevating cam, and automatically operating means for actuating the latter to perform in round knitting, in connection with the stitch cam means, regular knitting on all the needles for the main body 60 of the fabric and regular stitches on the short latch needles alternating with tuck stitches on the long latch needles for an anti-raveling course or courses of knitting, substantially as described.

65 2. In a circular knitting machine and in

combination, needles having short latches alternating with needles having long latches throughout the needle circle, a yarn feeder, stitch cam means, a movable needle elevating cam, which latter when raised, performs in 70 round knitting, in conjunction with the stitch cam means regular knitting on all the needles, and which when lowered permits said stitch cam means to make with the short latch needles regular stitches and with 75 said long latch needles tuck stitches alternating throughout the course or courses and means for operating the movable elevating cam, and a guard cam for restoring the elevated needles.

3. In combination in a circular knitting machine, needles having short latches alternating with needles having long latches throughout the needle circle, a yarn feeder, and needle cams including stitch and advancing cams, and a movable needle elevating cam, the latter cam when in its raised position elevating both the short and long latch needles to clear the loops from their latches onto their stems, a guard cam for 90 retracting all of the needles to their normal plane after being elevated to clear their loops, said advancing cam then advancing all the needles to receive the yarn and perform regular knitting and means for raising and lowering the movable needle elevating cam, the latter when in its lowered position allowing the needles to retain their loops on their latches until the advancing cam is reached which then advances all the 95 needles to take the yarn and clears the old loops below the short latches while maintaining the loops on the long latches for the formation of tuck stitches thereon alternating with regular stitches on the short latch 100 needles, substantially as described.

4. In combination in a circular knitting machine, needles having short latches alternating with needles having long latches throughout the needle circle, a yarn feeder, 110 stitch cam means, a movable needle elevating cam which latter when raised, performs, in conjunction with the stitch cam means, regular knitting on all the needles and which, when lowered permits said stitch cam means to perform regular knitting with the short latch needles and tuck knitting on the alternate or long latch needles, a pattern cam and a connection deriving a back and forth movement from said pattern cam 115 which it imparts directly to said movable needle elevating cam, substantially as described.

5. In combination in a circular knitting machine, needles having short latches alternating with needles having long latches throughout the needle circle, a yarn feeder, stitch cam means, a movable needle elevating cam which latter when raised, performs, in conjunction with the stitch cam 125 130

means, regular knitting on all the needles and which, when lowered permits said advancing cam to perform regular knitting with the short latch needles and tuck knitting on the alternate or long latch needles, a pattern cam having a high and a low part, a lever raised and lowered thereby, and a rod connecting said lever directly with the movable elevating cam, substantially as described.

6. In combination in a circular knitting machine, needles having short latches alternating with needles having long latches throughout the needle circle, said needles comprising an instep set and a heel and toe set having respectively long and short butts, an instep cam to elevate the long butt needles, stitch cam means, and a needle elevating cam in advance of the stitch cam

means on round knitting, and means for raising and lowering said cam, said cam when raised elevating the long and short latch needles, whether long or short butt, to perform in conjunction with the stitch cam means regular knitting on all the said needles and when lowered permitting said stitch cam means to perform regular knitting with the short latch needles and tuck knitting on the alternate long latch needles, whether long or short butt, substantially as described.

In testimony whereof, I affix my signature in presence of two witnesses.

EMIL BEDARD.
